B. S. BLAKE

TRELLIS

Filed Oct. 23, 1920

FIG. 1

FIG. 2

FIG. 3

INVENTOR
Byron S. Blake
BY
David V. Simms
his ATTORNEYS

UNITED STATES PATENT OFFICE.

BYRON S. BLAKE, OF ROCHESTER, NEW YORK.

TRELLIS.

Application filed October 23, 1920. Serial No. 419,006.

To all whom it may concern:

Be it known that I, BYRON S. BLAKE, a citizen of the United States, and resident of Rochester, in the county of Monroe and 5 State of New York, have invented certain new and useful Improvements in Trellises, of which the following is a specification.

The present invention relates to trellises and more particularly to the type which 10 employs horizontally arranged guy wires and vertical stakes, this type being most generally used in green houses for sustaining the branches of rose bushes or other plants. An object of this invention is to 15 provide a connection between the guy wires and the stakes which will permit the trellis to be readily collapsed in order that the work of dis-entangling the runners of rose bushes or other plants from the trellis may 20 be reduced to a minimum. Another object of the invention is to provide means for connecting the guy wires with the stakes, so that the guy wires may be moved longitudinally of the stakes to free the latter. A 25 still further object of the invention is to provide a clip of novel construction which may be secured to the guy wires of trellises for the purpose of tying the stakes in upright positions, while at the same time permitting the guy wires to be disconnected 30 from the stakes by a movement laterally and in the direction of the lengths of the stakes.

To these and other ends the invention 35 consists of certain parts and combinations of parts, all of which will be hereinafter described, the novel features being pointed out in the appended claims.

In the drawings:

Fig. 1 is a fragmentary sectional view 40 showing the manner in which a stake is held to a guy wire by one of the clips, the stake being shown in horizontal section and the guy wire in plan;

Fig. 2 is a view showing fragments of a 45 guy wire and a stake in elevation; and

Fig. 3 is a fragmentary view of a trellis 50 constructed in accordance with this invention.

Referring more particularly to the drawings, 1 indicates the stakes and 2 the guy wires which are secured in spaced relation 55 at their ends to suitable supporting means.

The feature of this invention is the con-

nexion between the guy wires and the stakes which will permit the guy wires to move 55 laterally in the direction of, or longitudinally of the stakes. This means, in this instance, embodies a clip formed from a single piece of wire into a straight central portion 3 and a portion 4 bent laterally 60 with reference to the central portion and then inwardly at 5 substantially parallel with the central portion. The other end of the clip is bent to provide a loop 6 at the side of the central portion on which 65 the laterally extending portion 4 is provided. This loop has one arm thereof forming the free end of the wire extended beyond the opposite side of the central portion 3 as at 7, one side being provided with 70 a depressed portion 8 forming a seat.

In using the clip, the loop portion 6 is passed about one of the stakes and the projecting portion 7 is passed under the string or guy wire. The central portion is then 75 positioned above the guy wire so that one arm of the loop 6 rests on the upper surface of the guy wire. The central portion is then deflected to carry the laterally extending portion below the guy wire 2 and 80 thereafter the clip is shifted so as to bring the laterally extending portion under and in engagement with the guy wire 2 as illustrated in the drawings. This causes the portion 5 to project upwardly slightly beyond the under surface of the guy wire and 85 thus prevent the accidental disengagement of the portion 4 with the guy wire 2. The loop loosely surrounds the stake 1 so that it is possible to move the guy wire with the 90 clip thereon laterally and in the direction of the length of the longitudinal axis of the stake, thus permitting the stake to be freed from the guy wire without any handling.

By this construction it is possible when 95 cleaning out the trenches in a greenhouse, to destroy the trellis without first disentangling the plant branches or runners from the guy wires and stakes, it being necessary only to elevate the guy wires and the stakes will 100 be freed as soon as such guy wires pass off the stake ends, thus permitting the use of the wire and the stakes for a new planting, the clips remaining in place to receive the stakes on the next building of the trellis. 105 The clips are of simple construction and are readily applied to secure the stakes in up-

right positions to the guy wires. Any stake may be removed at any time without removing the clips, and the clips slide on the guy wire so that they may be positioned at any desired point on a new planting.

What I claim as my invention and desire to secure by Letters Patent is:

1. A trellis comprising guy wires, vertical stakes, and stake securing means entirely supported by the guy wires and loosely surrounding the stakes to hold them in vertical position while permitting the wires to move longitudinally of the stakes to free the latter.
- 15 2. A trellis comprising guy wires, vertical stakes, clips detachably connected to and entirely supported by the guy wires and loosely engaging the stakes to hold them in position, the engagement being such that the guy wires may move longitudinally of the stakes.
- 20 3. A trellis comprising guy wires, vertical stakes, and clips detachably connected to and entirely supported by the guy wires, each clip being formed from a single piece of wire and having ends extending from opposite sides thereof and a loop between said ends, the clip resting upon one side a guy wire and having the ends engaging opposite

sides of the guy wire and the stakes extending loosely through the loop.

4. A clip comprising a straight central portion, two loops at the opposite ends of the central portion, each loop having the major portion thereof lying on one and the same side of the straight central portion, one of said loops opening to the side opposite that on which the loops project and having the arm nearest to the straight portion adapted to seat on one side of a cross wire, and the arm at the opposite end of the clip adapted to engage the opposite side of a cross wire.

5. A clip comprising a straight central portion, two loops at the opposite ends of the central portion, each loop having the major portion thereof lying on one and the same side of the straight central portion, one of said loops opening to the side opposite that on which the loops project and having the arm nearest to the straight portion adapted to seat on one side of a cross wire, the arm at the opposite end of the clip adapted to engage the opposite side of the cross wire, and the other loop having its outer arm extending inwardly in spaced relation to and at a slight angle to the central portion.

BYRON S. BLAKE.
